Primary Examiner — Brett Miller(74) *Attorney, Agent, or Firm* — Global IP Services; Tianhua Gu(57) **CLAIM**

The ornamental design for a portable power bank charger, as shown and described.

DESCRIPTION

FIG. 1 is a front elevational view of a portable power bank charger, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom perspective view thereof; and,

FIG. 8 is a top perspective view thereof.
